DRAFTING MACHINE

Eustace Russell Booth, Staines, England, assignor
of one-half to Sydney Marks, Feltham, EnglandApplication May 30, 1945, Serial No. 596,658
In Great Britain June 6, 1944

1 Claim. (Cl. 33—78)

1

This invention relates to drafting machines and more particularly to drafting machines in which the drawing board is rotatable relatively to its support and is adapted to be locked in various angular positions. The invention has for its object an improved and simplified construction of drafting machine of this kind.

In accordance with the invention there is pivoted to the support, which may be a pedestal, and which is provided with a socket or a spindle to receive a spindle, or a socket on the lower side of the drawing board, a pair of pivoted arms provided at their inner ends with toothed quadrants or the like adapted to mesh and carrying at their outer ends upstanding pins engaging in slots in a straight edge extending across the drawing board. The straight edge is thus guided parallel to itself over the board. The drawing board which is suitably provided on its periphery with angular graduations is fitted on its lower side with a disc or plate having angularly spaced notches or holes corresponding to the angular graduations on the periphery and adapted to be engaged by a spring-pressed pin supported on the pedestal. The pin is provided with a collar engaged by one end of a lever pivoted on one of the arms, the other end of the lever being located conveniently below and near the edge of the board. The pin is pressed normally by the spring into engagement with one of these notches or holes and holds the drawing board locked. To rotate the drawing board to a new angular position it is merely necessary to raise the outer end of the lever in order to depress the pin out of engagement with the notch or hole and when the drawing board has reached its new position to release the lever when the pin again engages one of the notches or holes on the disc and again holds the drawing board locked.

The invention is illustrated in the accompanying drawing in which Fig. 1 is a plan view of the improved drafting machine, Fig. 2 an elevation, Fig. 3 is a detail view of the releasing lever. Fig. 4 is a detail showing an adjustment for the drawing board and Fig. 5 a detail view of an auxiliary locking mechanism.

Referring to the drawings, 1 indicates a circular drawing board which is provided on its lower side with a tapered spindle 2 to engage a central socket on a support which is shown as a spider or tripod 3. Two of the legs 4 of the spider are provided with bearings 4a to receive pivot members 5 by which a pair of arms 6 are mounted for lateral movement, these arms being provided at their inner ends with toothed quadrants 7 adapted

2

to mesh. The arms 6 carry at their outer ends upstanding pins 8 engaging in slots 9 in a straight edge 10 which is supported by these pins slightly clear of the surface of the drawing board. Due to the meshing of the quadrants the arms 6 move together and the straight edge 10 is thus guided parallel to itself over the board. The swing or pivoting of the arms 6 is limited by pins 7a mounted in sockets in the legs 4 carrying the arms 6. The pins 7a extend through slots 7b in the respective webs of the quadrants 7. The drawing board is suitably provided on its peripheral edge with a metal rim 11 graduated in degrees and is fitted in its lower side with a centrally disposed disc or plate 12 having angularly spaced holes 13 corresponding to the angular graduations on the periphery and adapted to be engaged by a spring pressed pin 14 supported in one of the pivot members 5. The pin 14 is provided with a collar 15 engaged by one end of a lever 16 pivoted at 17 on one of the arms 6 as indicated in Figs. 2 and 3, the other end of the lever 16 being located conveniently near the edge of the board. The pin 14 is pressed normally by means of a spring 18 into engagement with one of the holes 13 and thus holds the drawing board locked. To rotate the drawing board to a new angular position it is merely necessary to raise the outer end of the lever 16 in order to depress the pin 14 out of engagement with the hole and when the drawing board is rotated to its new position to release the lever 16 whereupon the pin engages one of the holes in the disc 12 and again holds the drawing board locked.

In order to lock the drawing board in any intermediate position we may provide one of the legs 4 with an extension 19, as shown in Fig. 5, to which is secured a blade spring 20 provided at its outer end with a brake block 21. The blade spring is engageable by a screw 22. On rotation of the screw in one direction the brake block is pressed against the action of the blade spring 20 against the rim of the drawing board thus holding it in any desired position. The outer end of the blade spring 20 is inwardly bent as indicated in Fig. 5 to provide a pointer pointing to the graduations on the outer rim of the drawing board.

In order to tilt the board slightly the foot of one of the legs 4 of the pedestal may be screw-threaded and engaged by a screw 23. By turning the screw so that it projects beyond the foot, this leg 4, and with it the drawing board may be tilted.

On the pedestal may be fixed an annular rim

suitably marked which in conjunction with the rim on the drawing board can be used as a circular slide rule with the straight edge employed as a cursor.

I claim:

In a drafting machine, the combination with a drawing board having a support, of a pair of outwardly extending arms pivoted for lateral movement to the support below the board, each arm including a toothed quadrant at its inner end beyond its pivot point, the quadrants of the arms being meshed with each other so that the arms pivot about their pivot points simultaneously and to the same extent, a straight edge mounted over the board and connected to the outer ends of the pair of arms at points equidistant from the respective pivot points of the arms, the drawing board being rotatable with respect to the support, a spring-pressed pin carried by said support at the pivot point of one of said arms and adapted to engage the drawing board, and a lever pivoted

to said last-mentioned arm and arranged to depress said pin.

EUSTACE RUSSELL BOOTH.
